(57) **CLAIM**

The ornamental design for a cowling for an outboard motor, as shown and described.

DESCRIPTION

FIG. 1 is a front perspective view of a cowling for an outboard motor showing our new design;

FIG. 2 is a rear perspective view thereof;

FIG. 3 is a side view thereof;

FIG. 4 is an opposite side view thereof;

FIG. 5 is a front view thereof;

FIG. 6 is a rear view thereof;

FIG. 7 is a top view thereof; and,

FIG. 8 is a bottom view thereof.

The broken lines in the drawings illustrate portions of the cowling for an outboard motor that are not part of the claimed design.
